BUTTON SECURING DEVICE

Erik A. Nygard, Woonsocket, R. I.

Application September 22, 1951, Serial No. 247,787

7 Claims. (Cl. 24—110)

1

This invention relates to a button securing device sometimes referred to as button back, and is particularly adapted for use in the securing of a button having two studs projecting rearwardly in spaced relation from the rear face thereof.

One of the objects of this invention is to provide a button back which may be pressed into place on the button and will maintain itself in such relation until manually manipulated for release.

Another object of the invention is to provide a button back which will have a resilient action and will be of one piece of material.

Another object of the invention is to provide a button back which will be of extremely simple construction and yet strong and durable.

Another object of the invention is to provide a button back which will protect the prongs of the button from engaging or abrading the user or the clothing of the user.

With these and other objects in view, the invention consists of certain novel features of construction as will be more fully described and particularly pointed out in the appended claims.

In the accompanying drawings:

Figure 1 is an elevational view, showing in section a piece of fabric to which the button and back therefore are attached.

Figure 2 is a sectional view on line 2—2 of Figure 1.

Figure 3 is a sectional view at right angles to the section of Figure 2, showing the studs in dotted lines and the back in a position to secure the back to the studs.

Figure 4 is a view similar to Figure 3 but showing the parts as moved to a stud releasing position.

Figure 5 is a fragmental top plan view of one of the openings and one of the plates to show the gripping means and the free area of the openings adjacent thereto.

Figure 6 is a perspective view of the back before bent into final shape.

In proceeding with this invention, I cut from a strip of sheet stock of the required length, a blank which has a plate at each end in which there are located openings for accomplishing the results desired, while the stock intermediate these plates is of a flexible, resilient character which may be bent into a bowed or arched shape for aligning the openings as desired while permitting sliding of the plates for a different position of the openings.

With reference to the drawings the single

sheet of stock which is utilized for the button back is designated generally 10 and comprises a first flat plate 11 at one end of the strip which is shown in Figures 2, 3, and 4 and is the lower plate of the two plates there provided. This plate has a pair of openings 12—12 in certain spaced relation which is the spacing of the studs 13—13 extending rearwardly from the button 14 shown in Figures 1 and 2. At the opposite end 10 of this strip of stock 10 there is a second flat plate 15 which is in slidable contact with the plate 11 and is held in this contact by the edges 16 of the plate 11 being rolled over the edges of the plate 15 sufficiently loosely so as to guide the plates in a longitudinal movement. Plate 15 is provided with a first pair of openings 17—17 which are spaced the same as the openings 12 and which have fingers 18—18 extending inwardly from the opposite sides of the opening 17 so that when the studs 13—13 are passed through these openings 17 the fingers will flex upwardly as shown in Figure 2 and will grip the surface of the studs 13. This gripping will occur by reason of the sharp corners of the fingers 18, but in order that there may be a better holding, notches 19 may be placed in the studs 13 at diametrically opposite locations. A second pair of openings 20—20 are provided in the plate 15 adjacent the openings 17 as shown in Figures 5 and 6.

30 The middle or shank portion 21 of the plate 10 is bent sharply as at 22 and 23 where it extends from the plates 11 and 15 and is then arched on a short radius as at 24 and 25 and on a rather longer radius as at 26 connecting these shorter arch portions together. The stock is so bent that normally the openings 17—17 will align with the openings 12—12, but when pressure is applied as shown by the arrow 28 so as to arch the portion 26 greater as at 29 (see Figure 4), then the openings 20—20 will align with the openings 12—12 as shown in Figure 4.

By reason of this construction the button back may be pressed on to the studs 13—13 to assume the position shown in Figure 1, and if release is desired, pressure will be applied on the opposite sharply arched portions 24 and 25 to flatten these arches by causing the portion 26 to arch on a shorter radius so as to move the openings 17 from gripping relation with the studs 13 and cause the openings 20 to be in registry with opening 12 so that there will be no gripping on the stud and thus the button back may be lifted from the studs or the studs may be withdrawn from the fabric 30 through which they may extend.

By reason of the shank portion 21 connecting both the plates, the device is all formed from a single piece of sheet stock and studs are protected from abrasion with a person or the person's clothing upon which the button is mounted.

I claim:

1. A device for securing a two-post button in place, comprising a first plate having a pair of openings spaced and of a size to receive therethrough the posts of the button to be secured, a second plate in slidable contact with the first plate and having a first pair of openings spaced to register with the openings in the first plate and provided with resilient means to grip the posts and prevent movement of the posts in one direction therethrough and a second pair of openings free of gripping means and communicating with the first pair of openings and permitting the posts to move from the first pair of openings of the second pair of openings, elastically yielding means to urge the plates to move the first pair of openings in the second plate into registry with the pair of openings in the first plate but yieldable to align the second pair of openings in the second plate with the first pair of openings in the first plate for releasing the posts.

2. A device as in claim 1 wherein the plates are connected by a bowed resilient strip of material.

3. A device as in claim 1 wherein the plates are connected by a bowed resilient strip of material which is the same piece of material as the plates.

4. A device as in claim 1 wherein the edges of one plate are rolled over the edges of the other plate for slidably connecting the plates for movement one along the other.

5. In combination a button having two posts

extending therefrom, a device for gripping said posts comprising a first plate having a pair of spaced openings receiving therethrough the posts, a second plate in slidable contact with the first plate and having a first pair of openings spaced to register with the openings in the first plate and provided with resilient means gripping the posts and preventing movement of the posts in one direction therethrough and a second pair of openings free of gripping means and communicating with the first pair of openings and permitting the posts to move from the first pair of openings to the second pair of openings, elastically yielding means to urge the plates to cause the first pair of openings in the second plate into registry with the pair of openings in the first plate but yieldable to align the second pair of openings in the second plate with the first pair of openings in the first plate for releasing the posts.

20 6. A button as in claim 5 wherein the posts are provided with a plurality of axially spaced notches into which said gripping means extend.

25 7. A button as in claim 5 wherein the posts are provided with a plurality of axially spaced diametrically opposite notches into which said gripping means extend.

ERIK A. NYGARD.
